UNITED STATES PATENT OFFICE.

LOUIS G. BRINKMAN, OF DAYTON, OHIO.

TOY TELEPHONE.

Application filed July 21, 1924. Serial No. 727,386.

This invention relates to toys and particularly to a toy telephone in simulation of a desk phone, the invention consisting especially in the features of construction, 5 whereby the toy telephone may be manufactured economically.

Toy telephones of the present general type, and similar appearance are now quite commonly manufactured and sold. In common with the typical desk phone such toys embody a transmitter head and mouth piece mounted upon the upper end of a post supported in a base, from which extends a cord connected at its extremity to a receiver supported upon laterally projecting receiver hooks. Such toy telephones are ordinarily provided with a bell usually of the bicycle type. In many instances the bell is actuated by the removal of the receiver from the hook and by its replacement. In other instances, and as shown in the present drawing, the bell is independently actuated. The particular features of the present invention and mode of assembly can be applied to 25 either form of toy telephone whether equipped with an automatically actuated bell or an independently operated bell.

In the present toy there is contemplated an improved method of mounting the transmitter head comprising a coupling member stamped from sheet metal having angular disposed tines or fingers, one of which is downwardly directed to be driven into the upper end of the post or standard after being passed thru a perforation in a metal cap piece, from which the receiver hook extends. The other tine is directed laterally and slightly upward to receive successively the parts forming the transmitter head and 40 the mouth piece, which are perforated to receive such tine or finger, the end of tine being riveted or flared to secure the parts in position. Such coupling member is provided with a hole at a point aligned with both tines or fingers, which not only increases the resemblance to the ordinary telephone, but provides a convenient method of mounting the coupling member for the assembly of the transmitter head and mouth 45 piece, and also for engagement of a driving fixture to force the coupling member into the post or standard without marring or battering the edge of the coupling member.

Such toy telephones are ordinarily provided with a hole in the base thru which

the receiver cord is extended and knotted. In the present instance the base is provided with an indentation extending beneath the lower end of the post or standard, within 60 which the end of the receiver cord extends and is clamped between the base and the lower end of the standard or post, and is further secured by being transfixied by a nail, employed in securing the post to the 65 base.

The object of the invention is to simplify the construction and mode of assembly of toy telephones whereby they will be cheapened in construction capable of being 70 more easily and quickly assembled, will be strong and durable and unlikely to become broken or unjointed.

With the above primary and other incidental objects in view as will more fully 75 appear in the specification, the invention consists of the features of construction the parts and combinations thereof, and the mode of operation or their equivalents as hereinafter described and set forth in the 80 claims.

In the accompanying drawing wherein is shown the preferred, but obviously not necessarily the only form of embodiment of the invention, Fig. 1 is a perspective view 85 of the assembled toy telephone forming the subject matter hereof. Fig. 2 is a vertical sectional view showing the relation of the general parts and the mode of assembly. Fig. 3 is a perspective view showing the 90 mode of assembly of the coupling member by means of a fixture.

Like parts are indicated by similar characters of reference throughout the several views.

In constructing the toy telephone there is employed a base 1 stamped from sheet metal of concavo-convex form to the top of which the post or standard 2 is secured. Adjacent to the top or crown of the base 100 1 there is provided a radially disposed grooved depression 3, extending inwardly beneath the lower end of the post or standard 2. The end of the receiver cord 4 extends within such grooved depression 3, and 105 is clamped between the base 1 and the lower end of the post or standard 2. In addition to being clamped, the cord 4 is transfixied by a nail 5, which secures the base 1 and post or standard 2 in assembled relation. 110 Preferably tho not necessarily, the top or crown of the base 1 is slightly indented or

depressed as at 6 to receive the post or standard 2.

Secured to the upper end of the post or standard 2, which is preferably of wood, is a cap piece 7 from which projects laterally the receiver hook 8. The cap piece 7 and receiver hook 8 are stamped integrally from a single piece of metal. The receiver 9 is detachably supported upon hooks in 10 the usual manner.

To secure the cap piece 7 in place and to support the transmitter head and mouth piece, there is employed a coupling member 10, also stamped from sheet metal, having at 15 its lower end a tine or finger 11, which extends thru a centrally disposed slot in the cap piece 7 and is driven longitudinally in the upper end of the wooden post or standard 2. Extending laterally and slightly upwardly from the coupling member 10 is a 20 second tine or finger 12, which supports the transmitter head and mouth piece. The transmitter head is formed in two stamped sheet metal sections 13 and 14. The member 25 13 is of circular box like form, over the marginal edge of which the member 14 fits in the manner of a box lid. These members are provided with centrally disposed slots corresponding to the cross sectional area of the 30 finger or tine 12, which extends therethru and also thru a similar slot in the bottom of the stamped sheet metal mouth-piece 15. The transmitter head member 13 abuts against shoulders 16 formed upon the coupling member, and the parts are held in assembled relation by staking or riveting the 35 end of the finger 12. The preferred construction is to bifurcate the end of the tine or finger 12 as shown by dotted lines in Fig. 40 2, the furcations of which are bent outwardly or clenched within the interior of the mouth piece 15, to tightly secure the parts in assembled relation. To facilitate the assembly 45 of the toy and enable the transmitter head and mouth piece to be secured upon the finger or tine 12 and the finger or tine 11 to be driven into the post or standard 2 without battering or mutilating the coupling member 10, the coupling member is 50 provided with a hole 17 at the intersection of the axes, of the respective guides or fingers 11 and 12. For convenience of assembly the coupling member 10 is preferably located in a fixture 18, as shown in Fig. 3, in 55 which the coupling member 10 is inserted within a slot 19, with the tine or finger 12 projecting upwardly therefrom to receive the transmitter head parts and mouthpiece. A transverse removable pin 20 in the fixture 60 member 18 extends thru the opening 17 of the coupling member and receives the thrust of the staking, riveting or clenching operation necessary to secure the transmitter head and mouth piece in place. When so positioned in the fixture 18, the tine 11 projects

beyond the slot at one end thereof and may be driven into the post or standard 2 by blows delivered to the opposite end 21 of the fixture. A convenient and economical method of assembly is to force the nail 5 securing the base 1 into the post or standard 2 simultaneously with the engagement of the tine 11 in the opposite end of the post by means of an arbor press or some similar device by which pressure may be simultaneously applied to the fixture or holder, 18, for the coupling member 10 and to the base 1 and nail 5. During such assembling operation whether by means of a press or by hammer blows the impact or thrust necessary to drive the tine or finger 11 into the post or standard is received within the hole 17, thus protecting the margins of the coupling member 10. An alarm bell of the bicycle type shown at 22 is clamped to the 85 standard or post 2. In this instance the bell is actuated independent of the receiver by means of the thumb lever 23. Obviously other method of operating the bell may be resorted to while utilizing the structural features and assembly methods heretofore described.

From the above description it will be apparent that there is thus provided a device of the character described possessing the 95 particular features of advantage before enumerated as desirable, but which obviously is susceptible of modification in its form, proportions, detail construction and arrangement of parts without departing from 100 the principle involved or sacrificing any of its advantages.

While in order to comply with the statute the invention has been described in language more or less specific as to structural features, 105 it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

Having thus described my invention, I 115 claim:—

1. A toy telephone including a base supporting a post which in turn carries a transmitter head and mouth piece, characterized by a coupling member for the transmitter 120 head and post comprising a single integral piece stamped from sheet metal possessing angularly disposed tines one of which is driven into the top of the post, the other of which projects thru the transmitter head and mouth piece and is upset at its extremity to secure such parts in position.

2. A toy telephone including a base supporting a post which in turn carries a transmitter head and mouth piece, characterized 125

by a coupling member for the transmitter head and post comprising two integrally united angularly disposed tines, one of which penetrates the transmitter head and mouth piece and is secured by riveting, the other of which is driven into the end of the post.

5 3. A toy telephone including a base, supporting a post which in turn carries a transmitter head and mouth piece, characterized by a coupling member for the transmitter head and post comprising a single integral member extended to form angularly disposed tines, the member being shouldered adjacent to the tines, and a hole in said member at the intersection of the longitudinal axes of the tines, the transmitter head and mouth piece being mounted upon one of the tines and secured thereon by riveting, the other tine being driven into the end of the post.

20 4. A coupling piece for the transmitter head and supporting post of toy telephones comprising a single member having integral tines projecting in angularly disposed relation therefrom, the head being shouldered adjacent to said tines, one of the tines being for engagement with the transmitter head and the other tine for engagement with the supporting post.

25 5. A coupling piece for the transmitter head and supporting post of toy telephones comprising a single member having integral tines projecting in angularly disposed relation therefrom, said member having therein a hole at the intersection of the axes of said tines.

40 6. A coupling piece for the transmitter head and supporting post of toy telephones comprising a single member having integral tines projecting in angularly disposed relation therefrom, and means for engaging an abutment fixture therewith in position common to both tines for use in engaging one of said tines with the transmitter head and the other tine with the post.

7. A toy telephone including a base, supporting a post, which in turn carries a transmitter head and mouth piece, characterized by a metallic cap surmounting the post, a bifurcated arm integral with said cap forming a receiver hook, said cap being centrally perforated, and a coupling member to which the transmitter head is secured having a tine projected thru the perforation of the cap and driven into the upper end of the post.

50 8. A toy telephone wherein a base supports a post carrying a transmitter head and a support hook for a telephone receiver, characterized by an indentation radially disposed in the top of the base and extending beneath the post and a telephone receiver cord extending within said indentation and clamped between the post and base.

55 9. A toy telephone wherein a base supports a post carrying a transmitter head and a support hook, for a telephone receiver, characterized by a telephone receiver cord, the end of which is interposed between the base and the post and a retaining member common to said base, post and cord extending thru the base and interposed cord into the post.

60 10. A toy telephone wherein a base supports a post carrying a transmitter head and a support hook, for a telephone receiver, means for interconnecting the base and post characterized by a telephone receiver cord the end of which is interposed between the base and the post said interconnecting means clamping the telephone cord in such relation.

65 11. A base for a toy telephone comprising a concave convex sheet metal disc having a central perforation to receive a retaining member and further having a radially disposed grooved depression in its convex face in proximity to the central perforation.

70 In testimony whereof, I have hereunto set my hand this 8 day of July A. D. 1924.

LOUIS G. BRINKMAN.
